(57) **CLAIM**

I claim the ornamental design for a walking aid attachment, as shown and described.

DESCRIPTION

FIG. 1 is a perspective view of a walking aid attachment; FIG. 2 is a front view thereof; FIG. 3 is a rear view thereof; FIG. 4 is a left side view thereof, with the right-side view being a mirror image thereof; FIG. 5 is a bottom view thereof; FIG. 6 is a top view thereof; FIG. 7 is a perspective view of the walking aid attachment shown with the attachment extended out; FIG. 8 is a front view thereof; FIG. 9 is a rear view thereof; FIG. 10 is a left side view thereof, with the right-side view being a mirror image thereof; FIG. 11 is a perspective view of the walking aid attachment in an alternate state; FIG. 12 is a front view thereof; FIG. 13 is a rear view thereof; FIG. 14 is a left side view thereof, with the right-side view being a mirror image thereof; FIG. 15 is a bottom view thereof; FIG. 16 is a top view thereof; FIG. 17 is a perspective view of the walking aid attachment in an alternate state, with the attachment extended out; FIG. 18 is a front view thereof; FIG. 19 is a rear view thereof; and, FIG. 20 is a left side view thereof, with the right-side view being a mirror image thereof. The dash-dash broken lines depict portions of the article that form no part of the claimed design. Shading lines within the figures are for the purpose of illustrating the walking aid attachment's shape and are not features of the design.
